DESIGN FOR A PAIR OF SPECTACLES

Paul H. Johnston, Davenport, Iowa

Application May 2, 1940, Serial No. 92,088

Term of patent 14 years

To all whom it may concern:

Be it known that I, Paul H. Johnston, a citizen of the United States, residing at Davenport, in the county of Scott and State of Iowa, have invented a new, original, and ornamental Design for a Pair of Spectacles, of which the following is a specification, reference being had to the accompanying drawing, forming a part thereof.

In the drawing:

Fig. 1 is a perspective view of a pair of spectacles showing my new design; and

Fig. 2 is a plan view on an enlarged scale of one of the temples.

The essential features of the design reside in the parts shown in full lines.

I claim:

The ornamental design for a pair of spectacles, substantially as shown and described.

PAUL H. JOHNSTON.
